[57] CLAIM

The ornamental design for the top, front and side faces of a text keyboard or similar article, substantially as shown and described.

DESCRIPTION

FIG. 1 is a right side perspective view of the text keyboard showing my new design; some of the keys being indicated by dot-dash lines.

FIG. 2 is a top front perspective view thereof.

FIG. 3 is a front, right perspective view thereof.

FIG. 4 is a front elevational view thereof.

FIG. 5 is a left side elevational view thereof.

FIG. 6 is a right side elevational view thereof.

FIG. 7 is a rear elevational view thereof, the broken line portion is illustrative of environment and forms no part of the claimed ornamental design.
